SIGNORS TO TRICO PRODUCTS CORPORATION, OF BUFFALO, NEW YORK

HORN

Application filed October 3, 1930. Serial No. 486,228.

This invention relates to a fluid pressure operated horn for giving a warning note or signal, the same being primarily designed for use on automobiles, boats and other places where warning signals are to be given for attracting attention.

Heretofore various types and styles of horns have been devised for vehicular traffic, for boats and other uses, in which the horn or sound producing device has been actuated by a fluid pressure above atmospheric pressure. This compressed air factor has required special equipment and apparatus which increases the cost of production, adds to the weight of the device, requires a larger space for installation, and necessitates a high cost of upkeep. The apparatus commonly employed comprises a motor driven fan for creating a blast of air sufficient to produce the necessary note or signal in the horn. The motor, being electrically driven, places an additional burden upon the battery of the motor vehicle which is now so frequently called upon to function in the normal operation of the vehicle. Furthermore, the pressure of the blast of air acting on the sound emitting apparatus of the horn creates a piercing signal note which is unpleasing to the ear and quite annoying to all concerned.

The present invention aims to provide a warning signal or horn operable by a reduced pressure and in combination with the intake manifold of an internal combustion engine for producing a clear, distinct and well rounded signal note.

It is an object of the present invention to provide a warning signal which is of simple construction, capable of giving a pleasing though penetrating sound or note, and embodying a novel sound wave generator which is set in operation by the flow of atmospheric air that is induced by a negative pressure such as that derived from the intake manifold.

The invention further resides in the features of construction and the arrangements and combinations of parts hereinafter described in detail and succinctly claimed, reference being had to the accompanying drawings, wherein:

Fig. 1 depicts in elevation the present invention.

Fig. 2 is a longitudinal section through the horn.

Fig. 3 is a view of one section of the horn illustrating the mounting of the sound wave generator or valve, a portion of the latter being broken away for the sake of clearness.

Fig. 4 is a view similar to Fig. 2 depicting a modified manner of tone adjustment.

Referring more in detail to the accompanying drawings, the sound box or casing 1 is hollow, or chambered and comprises a front section 2 and a back section 3 suitably secured together, as by fasteners passed through holes 3a. The front section is formed with a tubular boss 4 on which is mounted the trumpet 5. Within the hollow section 2 is provided an annular valve seat 6 having communication with the trumpet 5 and being preferably adjustable, as by means of the threads 7, to permit the seat to be adjusted relative to the vibratory valve 8 which constitutes the sound wave generator, as will be more particularly referred to hereinafter. To facilitate the adjustment of the valve seat the latter may be connected to the trumpet 5, and by making it an integral part of the trumpet the adjustment of the valve seat is conveniently effected by simply turning the trumpet part 5 into or out of the boss 4. The threads 7 may project outwardly beyond the boss 4 to receive a jam or lock nut 9 by which the set adjustment of the valve seat is maintained. The passage of the trumpet, at its inner end, is preferably merged into a larger chamber 10 adjacent the valve seat 6.

The valve 8 is resiliently supported with respect to its seat 6, as by means of the radial springs 11 which are shown as four in number and extended under tension from the inner wall of the sound box to the valve 8, or a flange 12 connected thereto. To facilitate and simplify the construction the box section 3 is provided with anchoring portions 13 with which the outer ends of the springs are engaged, and the valve 8 is formed with an axial extension or hub 14 which carries the flange 12 to which the inner ends of the springs are connected. The springs there-

fore serve to resiliently hold the valve on its seat 6 so as to seal or close communication between the trumpet passage and the valve chamber 15 within the sound box, this engagement of the valve with its seat being made light or firm by the adjustment of the seat. Communication is established between the sound box and the intake manifold, or other source of suction, through a conduit 16, which communication is controlled by a readily accessible valve not shown.

The valve 8 may be formed independently of its hub or stem 14 and therefore may embody differing characteristics and materials in its make-up. The spring support for the valve permits bodily movement of the latter unguided otherwise in its movement than by the radial springs. Thus the valve is given a spring suspension permitting the valve to have bodily movement with or without a tension rocking or tilting motion. Therefore, the inertia of the rapidly moving vibrator 8, 14, is given tensioned as well as guided motion through the spring suspension.

In the operation of this horn the chamber 15 is placed in open communication with the intake manifold of the internal combustion engine, as a source of suction, by opening the conduit 16, whereupon a sub-atmospheric pressure will exist within the chamber 15, pulling the valve 8 from its seat 6, or permitting the higher atmospheric pressure within the trumpet 5 to push the valve inwardly from its seat. The atmospheric air entering through the trumpet and being exhausted through the conduit 16 establishes an air stream past the valve 8 and through the valve chamber 15. This unseating of the valve tends to equalize the pressures on both sides of the valve so that the springs will return the valve to its seat following which the pressure within the chamber 15 will again become rarefied and the valve unseat, and then reseat, whereby a series of condensations and rarefactions are produced in the air, with a resultant throwing of the air stream into vibration. The sound waves created by the seating and reseating of the member 8 on the annular ring or seat 6, or by the pulses or vibrations set up in the air stream, or by both combined, are modified, amplified, and varied by the trumpet passage.

The natural vibration period of the valve, for best results, should be substantially the same as the period of vibration of the sound waves in the trumpet. To this end the mass or body of the valve or vibratory member is such that the inertia of the valving member produces the required vibration period.

In our copending application filed March 21, 1931, Serial No. 524,342 we have described and claimed this tuned relationship between the periods of vibration of the valve and the air column in the trumpet or resonator.

In order to render the radial spring support for the valve more quickly responsive and improve upon the tone of the signal note, as well as increase its pitch, the springs 11 are given an intermediate support, as at 17, the support being conveniently carried by the box section 3. It may assume the form of an annulus or ring, integral with the box section, or this tensioning support may be made adjustable, as at 17', in which case it would be made as a separate part from the box housing. In Fig. 4 one form of adjustment is shown wherein the support 17' is provided with a stud 18 which is threaded through a boss 19, on the box section 3', and the adjustment is secured by a jam nut 20 engaged on the protruding end of the stud 18.

In the form shown in Fig. 4 the valve seat 6 may be fixed since the adjustment is obtained through the tensioning of the springs. In fact this spring tension adjusts the valve body toward or from its seat.

The sound passage of the trumpet opens through a restricted throat into the chamber 10 which enlarged chamber provides for a larger available surface to be acted upon by the suction, the suction when derived from the intake manifold being limited within certain confines. The throat restriction will further increase the intensity of the pulsations through the concentration at this point.

While in this description and in some of the appended claims the valve is referred to as normally engaging its seat when in idle or inoperative position, it is understood that the device may operate with a very slight clearance between the valve and the seat in normal or inoperative position of the valve and the valve move from that position in operation to and from the seat, and, therefore, this description and the appended claims should be read in the light of this understanding.

What is claimed is:

1. In combination with a source of reduced pressure, such as that which maintains in the intake manifold of an operating internal combustion engine, a hollow casing having a chamber provided with an exhaust opening connected to the source of reduced pressure by a conduit, a rigid annular seat in the chamber on the wall thereof, said casing having an inlet opening establishing communication between the outside atmosphere and the chamber through the annular seat, a sound wave generator normally engaging the seat to close the passage therethrough, said sound wave generator being of less diameter than the chamber, means separate from and resiliently supporting the sound wave generator against said seat whereby the sound wave generator will repeatedly unseat and seat to interrupt the air stream through the chamber and produce sound waves, and a trumpet connected to the chamber inlet opening acting in modifi-

cation of the frequency of the pulsations set up.

2. In combination with a source of reduced pressure, such as that which maintains in the intake manifold of an operating internal combustion engine, a hollow casing having a chamber provided with an exhaust opening connected to the source of reduced pressure by a conduit, a rigid annular seat in the chamber, said casing having an inlet opening through the seat, a valve in said chamber normally engaged with the seat, and resilient means supporting the valve for bodily movement from and to its seat, said valve being guided in its movements solely by said resilient means.

3. A suction operated horn comprising a chambered casing having an inlet seat, a trumpet communicating with the chamber through the seat, a valve, spring means extending radially from the valve for supporting the latter within the chamber, said spring means being connected to the surrounding wall of the chamber, means within the casing for supporting the springs, intermediate their ends and against the unseating of the valve, means for adjusting said spring supporting means to vary the tension on said springs, and means for connecting the chamber to a source of suction.

4. A suction operated horn comprising a hollow casing having a chamber with an annular seat and a surrounding side wall, a trumpet communicating with the chamber through the seat, a valve having a stem axial of the seat, resilient means normally holding the valve on said seat, said means engaged with the valve stem and supporting the valve from the side wall for bodily movement, and means for connecting the chamber to a source of suction.

5. In combination with a source of reduced pressure, such as that which maintains in the intake manifold of an operating internal combustion engine, a hollow casing having a chamber provided with an exhaust opening connected to the source of reduced pressure by a conduit, a rigid annular seat in the chamber, said casing having an inlet opening through the seat, a valve normally engaged with the seat, and resilient means supporting the valve for bodily movement from and to its seat, said valve being guided in its movements solely by said resilient means, the latter comprising a plurality of coiled springs connected at their inner ends to the valve and at their outer ends to the casing.

6. A horn comprising a hollow casing having an inlet seat, a trumpet communicating with the casing chamber through the seat, a valve, coiled springs extending radially from the valve for supporting the latter within the box chamber, said springs being connected at their outer ends to the casing, means within the casing for supporting the springs inter-

mediate their ends and in opposition to the seat, and an outlet port from the casing chamber.

7. In a horn, means for receiving a column of atmospheric air, said means including an amplifying horn portion and having at its inner end a substantially rigid open seat delineating an air admission opening, a chamber in communication with said inner seat, said chamber being of larger cross sectional area than the opening through said seat, a suction line in communication with said chamber, said suction line being of smaller cross sectional area than said air admission opening, a movable closure member for said air admission opening in said chamber, said closure member being of lesser diameter than said chamber, means for supporting said closure member for movement in said chamber and normally in closed relation to said air admission opening whereby the application of suction to said suction line causes said closure member to alternately seat and unseat thereby generating sound waves in said horn.

8. A horn comprising a hollow casing having an inlet seat, a trumpet communicating with the casing chamber through the seat, a valve, a plurality of springs disposed radially about the valve and supporting the latter within the casing chamber, and an outlet port from the casing chamber.

9. A fluid operated horn comprising a hollow casing having an atmospheric inlet opening in one side, a trumpet having its smaller end adjustable in the inlet opening and having an annular valve seat on said end within the casing, a resilient valve within the chamber of the casing normally engaging the seat, said trumpet being adjustable to vary the seat relative to the valve.

10. In combination with a source of reduced pressure, such as that which maintains in the intake manifold of an operating internal combustion engine, a hollow casing having a chamber provided with an exhaust opening connected to the source of reduced pressure by a conduit, a rigid annular seat in the chamber, said casing having an inlet opening through the seat, a valve normally engaged with the seat, resilient means supporting the valve for bodily movement from and to its seat, said valve being guided in its movements solely by said resilient means, the latter comprising a plurality of coiled springs connected at their inner ends to the valve and at their outer ends to the casing, an intermediate support engaged with each spring intermediate its ends and in opposition to the seat, and means for adjusting said intermediate support to vary the tensioning of said springs.

11. In combination with a source of reduced pressure, such as is maintained in the intake manifold of an operating internal combustion engine, a hollow casing having

a chamber provided with an inlet opening defining a valve seat within the chamber at the inner side of and about the inlet opening, a valve within the chamber closing outwardly against the seat, resilient means supporting the valve for bodily movement from and to its seat, and means for establishing an air stream into the chamber through the inlet opening, said valve moving from and to its seat entirely within the chamber and closing to its seat in opposition to the flow of the air stream.

12. In combination with a source of reduced pressure, such as is maintained in the intake manifold of an operating internal combustion engine, a hollow casing having a chamber provided with an inlet opening, a resonator for the casing, a valve seat within the chamber through which communication is had through the inlet opening with the resonator, a valve within the chamber closing outwardly against the seat and toward the resonator, a stem on said valve, spring supporting and guiding means in said chamber for said valve and stem, and means at the valve side of the seat for establishing an air stream into the chamber through the inlet opening, said valve moving from and to its seat entirely within the chamber and closing to its seat in opposition to the flow of the air stream.
